CHOCOLATE BAR OR SIMILAR ARTICLE

Edmond Opler, Hinsdale, Ill., assignor to Cook Chocolate Company, Chicago, Ill., a corporation of Illinois

Filed Apr. 16, 1965, Ser. No. 84,831

Term of patent 14 years

(Cl. D82—2)

FIG. 1 is a top plan view of a chocolate bar showing the new design.

FIG. 2 is a cross-sectional view taken on line 2-2 of FIG. 1.

FIG. 3 is a cross-sectional view taken on line 3-3 of FIG. 1.

FIG. 4 is a side elevational view of the chocolate bar shown in FIG. 1.

I claim:

The ornamental design for a chocolate bar or similar article, substantially as shown.
